United States Patent

Des. 240,804
Patented Aug. 3, 1976

240,804

POSTAL SCALE

Frank C. Rock, Santa Rosa, and Fred Lahira Moore,
Petaluma, Calif., assignors to National Controls, Inc.

Filed Sept. 30, 1974, Ser. No. 510,452

Term of patent 14 years

Int. Cl. D10—04

U.S. Cl. D10—91

FIG.-1

FIG.-2

FIG. 3

Des. 240,804

Page 2 of 2

FIG. 4

FIG. 1 is a right front perspective view of a postal scale showing our new design;

FIG. 2 is a rear elevational view thereof;

FIG. 3 is a top plan view thereof;

FIG. 4 is a right side elevational view thereof, the left side being a mirror image thereto.

The digital readout numbers shown are typical and form no part of the ornamental design.

We claim:

The ornamental design for a postal scale, as shown and described.
